[57] CLAIM

The ornamental design of a boat deck, as shown and described.

DESCRIPTION

FIG. 1 is a top plan view of the boat deck of this invention;

FIG. 2 is a right-hand side view thereof, the left-hand side view appearing the same;

FIG. 3 is a rear view; and

FIG. 4 is a front view.

The broken line disclosure of a boat hull is shown for illustrative purposes only.
